UNITED STATES PATENT OFFICE.

ARTHUR MILLER, OF COLUMBUS, OHIO, ASSIGNOR TO THE SOLAR METAL PRODUCTS COMPANY, OF COLUMBUS, OHIO, A CORPORATION OF OHIO.

METAL RECEPTACLE.

Application filed March 3, 1921. Serial No. 449,331.

To all whom it may concern:

Be it known that ARTHUR MILLER, a citizen of the United States, residing at Columbus, in the county of Franklin and State of Ohio, has invented certain new and useful Improvements in Metal Receptacles, of which the following is a specification.

This invention relates to improvements in sheet metal receptacles, and has particular reference to such like metallic cans or containers as are commonly employed in connection with ice cream freezers and for other analogous uses.

The object of the invention resides in the provision of a sheet metal receptacle of the character stated which may be cheaply and economically manufactured and which will possess strength and rigidity so as to enable the same to withstand successfully the pressures and jars of ordinary handling.

More particularly, the invention consists in the provision of a metallic receptacle wherein is found a lower joint structure, between the wall of the can and the bottom thereof and to construct this joint structure so as to provide an inwardly offset flange upon the lower end of the can body or wall, which has its edge arranged to be welded to the outer edge of the bottom member, and to provide a reinforcing ring around the joint between the body and the bottom member, which ring is so positioned as to engage the inwardly offset flange of the body and to protect the welded joint so that a firm, substantial and effective union between the body and bottom members will be established.

A further object of the invention resides in the provision of a joint structure of this nature wherein the use of rivets, bolts and other analogous fastening elements are eliminated, and to accomplish this in such manner that the rigidity and strength of the can will be maintained and yet to permit of a more economical manufacture thereof over structures involving such fastening elements.

For a further understanding of the invention reference is to be had to the following description and to the accompanying drawing, forming a part of this specification, in which similar characters of reference denote like and corresponding parts throughout the several views of the drawing.

In said drawing:

Figure 1 is a vertical sectional view taken through a metallic receptacle constructed in accordance with the principles of the invention, and

Figure 2 is an enlarged sectional view disclosing more particularly the improved joint structure thereof.

Referring more particularly to the drawings, the numeral 1 designates the improved sheet metal receptacle comprising the present invention in its entirety. As shown, the receptacle is formed to comprise a cylindrical body 2, which has its upper end bent downwardly upon itself as at 3 and reinforced by means of a ring 4 which ring may be welded or otherwise secured to the lower portion of the downwardly bent edge 3. By this construction the upper end of the receptacle is suitably reinforced to enable closure or the like, not shown, to be readily and firmly associated therewith in a tight liquid sealing manner. The lower end of the body 2 is bent inwardly to provide an annular shoulder 5, which terminates in a depending circular flange 6. Adapted to be connected with this flange is the bottom member 7 of the receptacle. In its preferred form this member is of dished cross-sectional formation and provides an upwardly flaring outer circumferential portion 8. The extreme outer edge of the portion 8 constitutes a seat for the lower edge of the flange 6, and the latter is bent inwardly in such manner that the same will gradually merge into flush and even engagement with the portion 8; the inwardly bent portion of the flange 6 being designated by the numeral 9. This construction serves to eliminate sharp corners or crevices in the internal construction of the can. Also, the joint formed between the body 2 and the bottom member is rigidly established by gas welding the portion 9 to the outer edge 8 of the bottom member.

This construction enables a secure union to be established between the body and bottom members without the use of rivets.

The bottom member after forming the edge 8 is bent downwardly to provide a vertical annular wall 10, which extends an appreciable distance below the plane of the bottom member so that the latter will be elevated above the base upon which the receptacle rests or is placed. To reinforce this

construction a band 11 is forced on the wall 10 so as to surround the latter, and said band is of such height that its upper edge will overlap the joint between the body and bottom members and will engage with the shoulder 5 formed by producing the flange 6. When so positioned, the band 11 may be secured in place by spot-welding the same to the wall 10. From this construction it will be apparent that by use of the wall 10 and the band 11 a strong and substantial base construction will be provided for the receptacle and also one which will capably protect the welded joint between the body and bottom members. By engaging with the shoulder 5 the band 11 prevents stresses and jar from being imparted to the welded joint, and thus enables the latter to be successfully employed without separation under the severe conditions of practical usage. Moreover, the construction eliminates the use of fastening elements without in any way effecting the general strength and rigidity of the receptacle. The internal construction of the can is characterized by its smoothness and absence of inaccessible pro-

jections or crevices therein, a feature which materially contributes toward maintaining the can in a sanitary condition.

What is claimed is:

In a sheet metal receptacle, a tubular body member having its lower end formed with an inwardly directed annular shoulder and a depending vertical flange, said flange having its lower edge curved inwardly, a bottom member having its outer edge arranged to constitute a seat for the lower curved edge of said flange and forming, in effect a continuation thereof, and to enable said flange to be welded to said edge, an annular wall depending from the outer edge of said bottom member, and a reinforcing band arranged to encircle said wall and lower end of the body and to be welded thereto, said ring having its upper portion positioned to engage said shoulder and to surround and protect the joint between the body and bottom members.

In testimony whereof I affix my signature.

ARTHUR MILLER.
